UNITED STATES PATENT OFFICE.

WARREN W. BAIRD, OF PITTSBURGH, PENNSYLVANIA.

VENTILATOR FOR WINDOWS.

1,217,897.

Specification of Letters Patent.

Patented Mar. 6, 1917.

Application filed March 6, 1916. Serial No. 82,302.

To all whom it may concern:

Be it known that I, WARREN W. BAIRD, a citizen of the United States, residing at Pittsburgh, in the county of Allegheny and State of Pennsylvania, have invented certain new and useful Improvements in Ventilators for Windows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improvement in ventilators for window use, and it comprises a device adapted to be placed beneath the window sash, and resting upon the window sill and held in position by the weight of said sash.

The invention further consists in a means whereby the air currents entering the room, may be deflected upward, downward or in both directions at one and the same time, or said currents may be shut off entirely.

The invention further consists in providing sliding extension pieces at each end of the body-portion of the ventilator, whereby the same may be adjusted to fit windows of varying widths, and the invention still further consists of the certain details of construction and combination of parts, as will be fully described hereinafter.

35 In the accompanying drawings:—

Figure 1 is an end sectional elevation of my improved ventilator, showing the same positioned beneath the sash and within the frame of a window, the section through the 40 ventilator being indicated by the line Y Y, on Fig. 3.

Fig. 2 is an end section taken on the line *w, w*, Fig. 3.

Fig. 3 is an inside elevation of the 45 ventilator.

Fig. 4 is an edge view of the body-portion of the ventilator.

To construct a ventilator in accordance with my invention, I first provide a rectangular shaped body-portion 3, preferably of wood, and provided with a rectangular opening 6, extending in the direction of the length of said body. This body-portion 3,

is formed along its top edge with a tongue 4, to engage with the window sash 1, and the bottom edge with a similar tongue 5, to engage with the window sill 2, below. Covering the opening 6, is a wire netting 7, and an outwardly-projecting hood 8, said hood being open at the base and having closed ends. 60 Attached to the body-portion 3, and at either end of the opening 6, are two outwardly-extending brackets 9, having slots 10, adapted to receive threaded pins 12, attached at either end of a lid or cover 14, which is 65 adapted to close or cover the opening 6. This cover 14, I prefer to be dished or in semi-circular form and having closed ends. The screw pins 12, attached to each end of the cover are fitted with thumb nuts 12', 70 which when tightened or screwed against the brackets 9, and the cover adjusted to the desired position, will hold the latter rigid.

Each end of the body-portion 3, is slotted vertically to receive slideable extension pieces 75 16, adapted to be moved in the direction of the length of said body, and held by thumb screws 18, said screws operating in longitudinally-arranged slots 15. This construction will permit adjustment to accommodate 80 the device to windows of varying width.

At Fig. 1, of the drawings, the cover 14, is adjusted to entirely cover and close the opening 6, and in dotted lines the cover is shown in an altered position, which position 85 will deflect the air currents upward and downward, as indicated by the arrows shown in dotted lines.

At Fig. 2 of the drawings, the cover 14, is set to deflect the air currents downward, 90 and on the same figure, the cover is shown in dotted lines in a position whereby the air currents will be directed upward.

The four positions of the cover 14, as above described, give the person using the 95 ventilator the choice of deflecting the air currents entering the room in the several directions above mentioned.

Having thus described my invention, I claim:—

100 A ventilator for window use, comprising a rectangular body portion having a longitudinal opening, means comprising a tongue formed along the top edge of said body portion for engaging with the lower rail of a 105 window sash, and similar means for engag-

2
ing with the window sill formed along the length of the bottom edge of said body-portion, whereby said body may be held in a vertical position, slotted brackets arranged at either end of said opening, a cover adapted to close said opening, threaded pins attached to either end of said cover, said pins projecting through said slots, and suit-

able thumb nuts operating upon said pins to clamp said cover at varying positions. 10

In testimony whereof, I affix my signature, in presence of two witnesses.

WARREN W. BAIRD.

Witnesses:

H. E. HARRISON,
OTTO A. HENSEL.
